Des. 233,322
Patented Oct. 22, 1974

233,322

TRAILER ASSEMBLY

Francis W. Schantz, Melvindale, Mich., assignor to
Francis W. Schantz, Melvindale, Mich.

Filed June 7, 1973, Ser. No. 367,794

Term of patent 14 years

Int. Cl. D12—10

U.S. Cl. D12—97

FIG. 1 is a front elevation of the trailer assembly;
FIG. 2 is a rear elevation of the trailer assembly;
FIG. 3 is a top plan view of the trailer assembly; and
FIG. 4 is a side elevation of the trailer assembly.

The broken lines shown in FIGS. 1 and 4 are for illustrative purposes only.

I claim:

The ornamental design for a trailer assembly, as shown and described.
